UNITED STATES PATENT OFFICE

HARRY B. ARCHER, OF DOLGEVILLE, NEW YORK

COMPRESSED-AIR ENGINE

Application filed December 3, 1929. Serial No. 411,304.

This invention relates to compressed air engines and more particularly to devices of this character of the reciprocating piston type wherein a piston is mounted for reciprocatory movement in a cylinder into which the charge of compressed air is alternately admitted on opposite sides of the piston in a manner to actuate the same.

An important object of the invention is to provide, in a manner as hereinafter set forth, a compressed air engine of the aforementioned character having associated therewith a valved compressed air reservoir or tank wherein the valves are provided with means actuated by the motor for properly operating the same.

Another important object of the invention resides in the provision of automatically operated means in the form of a reciprocating valve for exhausting the air from the cylinder.

Other objects of the invention are to provide a compressed air engine which will be simple in construction, strong, durable, efficient in its use and which may be manufactured at low cost.

Still further objects and advantages of the invention will become apparent from a study of the following specification, taken in connection with the accompanying drawings wherein like characters of reference designate corresponding parts throughout the several views, and wherein:

Figure 1 is a view in side elevation of a compressed air engine constructed in accordance with this invention.

Figure 2 is a vertical cross-sectional view, taken substantially on the line 2—2 of Figure 1 and looking in the direction of the arrows.

Figure 3 is a vertical longitudinal sectional view thereof.

Figure 4 is a detail view in side elevation showing the means for connecting the intake valve operating lever with said intake valve in a manner to actuate the same.

Figure 5 is an end view of Figure 4.

Figure 6 is an enlarged detail view in perspective of the reciprocating exhaust

valve, the same being shown turned upside down.

Referring to the drawings in detail, the reference character 1 designates an elongated cylinder having one end closed through the medium of a removable head 2 secured by the threaded bolts 3 to a flange 4 on the adjacent end of the cylinder. The head 2 is provided with a centrally disposed opening and a packing flange 5 through which slidably extends a rod 6 upon the inner end of which is mounted the piston 7.

Adjacent its opposite end, the cylinder 1 is provided with laterally extending internally threaded necks 8 for the reception of one end of the threaded conductor pipe designated generally by the reference character 9. The upper ends of the air conductor pipe 9 are threaded into the side of a compressed air reservoir or tank 10 through the medium of the laterally extending internally threaded necks 11 and the upper end of said pipe 9 extends a slight distance into the reservoir 10 to provide a valve seat 12 (see Figure 3). The opposite ends of the reservoir 10 are closed by removable heads 13 secured to the flanges 14 by the threaded bolts 15. Brackets 16 are vertically disposed in the reservoir 10 at a point adjacent the valve seat 12 and pivotally mounted on the upper end portion of said bracket is a valve 17 adapted to seat on the adjacent seat 12 for controlling the passage of air therethrough. These brackets 16 are bifurcated and the valves 17 are pivotally mounted therebetween, as at 18, and said valves are provided with a rearward extension 19 between which extension, adjacent its free end, and the wall of the reservoir 10 is interposed an expandable coil spring 20 which normally maintains the valves 17 on the adjacent seat 12. Above the extension 19, the wall of the reservoir 10 is provided with openings 21 and packing flange 22 through which slidably extends a pair of valve actuating push rods 23 the lower ends of which are engaged on said extension 19. The push rods 23 have their upper ends provided with bifurcated heads 24 for the reception of the downwardly extending protuberances 25 on the opposite end of a rocking beam 26 which

is pivotally mounted for vertical adjustment on the reservoir 10 through the medium of a threaded standard 27 which has its lower end threadedly engaged in a socket 28 on the reservoir and the upper end of which is provided with a bifurcated head 29 between the furcations of which the rocking beam 26 is pivotally supported, as at 30. The nut 31 is threaded on the standard 27 for engagement with the upper end of the socket member 28 for securing the standard in adjusted position.

Exhaust passages 32 communicate with the cylinder 1 adjacent its opposite end and at a point diametrically opposed to the threaded necks 8. As seen in Figure 3 of the drawings, the passages 32 extend longitudinally in the lower wall of the cylinder 1 toward the center thereof and are then directed outwardly and communicate with the interior of a valve chest 33 which is secured, as at 34 to said cylinder 1. The valve chest 33 is provided with a removable closure plate 35 secured thereto by the bolt 36 and provided with a flange 37 which projects into the valve chest adjacent the wall thereof and terminates in spaced relation with respect to the wall of the cylinder 1, as clearly seen in Figure 3 of the drawings. The free end of the flange 37 provides a shoulder in the valve chest 33 upon which is mounted for reciprocation a slide valve 38 which is provided with a transverse port 39 adapted to be brought into registry with the outer ends of the exhaust passages 32. The valve 38 is provided, on its lower side, with depending ears 40 provided with longitudinally extending slots 41 for slidably receiving the T-heads 42 of the rods 43 which slidably extend through one end wall of the valve chest 33, as at 44. A supporting arm 45 is rigidly secured to the removable head 2 of the cylinder 1 and has pivotally mounted on its free end and at the intermediate portion thereof a lever 46 which is operatively connected with the piston rod 6 through the medium of a pin and slot connection 47. The lower end of the lever 46 is operatively connected to the rod 43 through the medium of the connecting link 48. An exhaust pipe 49 communicates with the interior of the valve chest 33 on the lower side thereof.

A supporting arm 50 is rigidly secured, as at 51, to one of the removable heads 13 of the reservoir 10 and on the free end of said arm 50 the intermediate portion of an actuating lever 52 is pivotally mounted, as at 53. One end of the lever 52 is operatively connected to the piston rod 6 through the medium of the pin and slot connection 54. A vertically disposed standard 55 extends upwardly from the top of the reservoir 10 and is provided with a longitudinally extending head 56 on its upper end having upstanding flanges 57 on its longitudinal side to provide a channel for the slidable reception of a block

58 (see Figures 4 and 5). As seen in Figure 5 of the drawings, the head 56 is disposed adjacent the rocker beam 26 and on one side thereof. As seen most clearly in Figure 4, the block 59 is provided with a slot or recess 59 which comprises a pair of horizontally disposed longitudinally extending portions which have communications with each other through a diagonally extending portion 60. The slot 59 is for the reception of a horizontally disposed pin 61 which projects laterally from the adjacent side of the rocking beam 26. The block 58 is provided with a rearward extension 62 in the free end portion of which is disposed a transversely extending pin 63 which projects from the opposite side of the extension. A link 64 is provided with a bifurcated free end portion which embraces the extension 62 of the block 58 and is provided with a longitudinally extending slot in each of its furcations for the reception of the projecting end of the pin 63 and said slots are designated by the reference character 65. The opposite end of the element 64 is pivotally connected to the adjacent end of the actuating lever 52 as at 66.

Means for supplying air under compression to the reservoir 10 is provided through the medium of a valved inlet 67 which is controlled through the medium of an actuating rod 68 pivotally connected to an arm 69 of the valve which is disposed in the air supply conduit 67 adjacent said reservoir.

When the engine is in operation, the piston 7 reciprocates in the cylinder 1 and the lever 52 is rocked on its pivot 53 through the medium of the pin and slot connection 54 with the piston 6 and the slot 58 is caused to reciprocate on the head 56 of the standard 55. The rocking beam 26 is thus actuated through the medium of the laterally projecting pin 61 which is disposed in the recess or slot 59 of the block 58, said pin moving into the different horizontally disposed portions of the recess as the slot reciprocates for imparting movement to the rocking beam 26. The beam 26 alternately unseats the valves 17 and air under pressure which is stored in the reservoir 10 passes through the conduit 9 and alternately enters the cylinder 1 on opposite sides of the piston 7, as will be obvious. The reciprocation of the piston 7 and the rod 6 also imparts movement to the lever 46 through the medium of the pin and slot connection 47 for reciprocating the valve 38 in the valve chest 33 and the movement of said valve is so timed with respect to the piston 7 and the valves 17 and as air is admitted to the cylinder on one side of said piston the port 39 in the valve registers with the exhaust passage 32 which has communication with the opposite side of the piston. The slot 65 in the element 64 travels over the ends of the pin 63 in the extension of the block 58 and said block is of such length that the head 56 will

be actuated only when the lever 52 approaches the end of its rearward and forward strokes. Air from any suitable source is stored under pressure in the reservoir 10 through the medium of the valved inlet 67. It is further pointed out that the connection provided by the cross head 42 in the slots 41 of the valves 38 provide means whereby said valves will be actuated only when the lever 46 approaches the end of each stroke.

It is believed that the many advantages of a compressed air engine constructed in accordance with this invention will be readily understood, and although the preferred embodiment of the invention is as illustrated and described, it is to be understood that changes in the details of construction may be had which will fall within the scope of the invention as claimed.

What is claimed is:—

1. A compressed air engine of the character described comprising a cylinder, a piston mounted for reciprocation in the cylinder, a piston rod connected to the piston, a reservoir adapted to contain air under pressure mounted on the cylinder in spaced parallelism therewith, pipes communicating with the reservoir and with the cylinder adjacent opposite ends of the latter, valve seats disposed in the reservoir on the ends of the pipes, pivoted valves disposed within the reservoir and adapted for engagement on the valve seats, integral tails on the valves, coil springs engaged with the tails and the adjacent wall portions of the reservoir for yieldingly urging the valves toward closing position, push rods slidably extending through the wall of the reservoir and engaged with the tails for alternately opening the valves for admitting air to the opposite ends of the cylinder, a rocking beam adjustably and pivotally mounted on the exterior of the reservoir and having its opposite ends engaged with the adjacent ends of the push rods for actuating the latter, means actuated by the piston rod for rocking said beam and means actuated by the piston rod for exhausting the air from the cylinder.

2. A compressed air engine of the character described comprising a cylinder, a piston mounted for reciprocation in the cylinder, a piston rod connected to said piston, a compressed air reservoir associated with the cylinder, pipes communicating with the reservoir and with the opposite end portion of the cylinder, said pipes extending into said reservoir, valve seats formed on the ends of the pipes within the reservoir, spring controlled valves pivotally mounted in the reservoir adjacent the pipes and adapted to seat on the valve seats for closing the pipes, push rods slidably extending into the reservoir for engagement with the valves for alternately opening the same, a rocking beam having its intermediate portion pivotally mounted on

the reservoir, the opposite ends of said beam in engagement with the adjacent ends of the push rods for alternately opening the valve in the reservoir, means for rocking said beam comprising a standard mounted on the reservoir, a channelled head on the free end of the standard and adjacent the rocking beam, a block slidably mounted in the channelled head and having a recess having connected horizontally disposed portions vertically offset with respect to each other, a pin extending laterally from the rocking beam and disposed in the recess, a lever pivotally mounted on the reservoir, and connected to the piston rods for actuation thereby, said lever operatively connected to the slot for imparting reciprocatory movement thereto and means for exhausting the air from the cylinder.

In testimony whereof I affix my signature.

HARRY B. ARCHER.
